UNITED STATES PATENT OFFICE.

CHARLES R. HARRIS, OF WILLIAMSPORT, PENNSYLVANIA.

DESIGN FOR A RECEPTACLE.

SPECIFICATION forming part of Design No. 30,763, dated May 16, 1899.

Application filed April 22, 1899. Serial No. 714,114. Term of patent 14 years.

To all whom it may concern:

Be it known that I, CHARLES R. HARRIS, of Williamsport, in the county of Lycoming and State of Pennsylvania, have invented a new 5 and original Design for Receptacles, of which the following is a full, clear, and exact description, reference being had to the accompanying drawing, forming a part thereof.

The accompanying drawing is a view in perspective illustrating my improvements.

The leading and important feature of my design consists of an angular receptacle having longitudinal corrugations.

15 A represents an angular body bulged outward at its central portion, as shown at 1, and 2 represents a series of longitudinal corruga-

tions all around the body A. The top and bottom of the body A are made with a peripheral flange or extension 3, and the body is provided on diametrically opposite sides in proximity to the flanged upper end with depressions 4, and the lower portion of the body is made with a depression 5 and a plug or bung 6 in the depression. 20

What I claim is—

25 The design for a receptacle herein shown and described.

CHAS. R. HARRIS.
